Primary Examiner — Michelle E. Wilson

(57) **CLAIM**

The ornamental design for a speaker lamp, as shown and described.

DESCRIPTION

FIG. 1 is a top, front and right side perspective view of a speaker lamp showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 2.

The dash-dash broken lines in the drawings illustrate portions of the speaker lamp which form no part of the claimed design.

The dot-dash broken lines in FIGS. 1, 2, 9 and 10 illustrate boundaries of the enlarged portions which form no part of the claimed design.

The oblique shade lines in the drawings represent reflective surfaces.

1 Claim, 10 Drawing Sheets
